UNITED STATES PATENT OFFICE.

FRANK E. McALLISTER, OF MINNEAPOLIS, MINNESOTA.

CHECK-PROTECTOR.

1,401,168.

Specification of Letters Patent. Patented Dec. 27, 1921.

Application filed May 25, 1921. Serial No. 472,357.

To all whom it may concern:

Be it known that I, FRANK E. McALLISTER, a citizen of the United States, residing at Minneapolis, in the county of Hennepin 5 and State of Minnesota, have invented certain new and useful Improvements in Check-Protectors; and I do hereby declare the following to be a full, clear, and exact description of the invention, such as will enable 10 others skilled in the art to which it appertains to make and use the same.

This invention relates to a perforating or mutilating device which is adapted to form in one of its uses a check protector. The 15 device is of the type in which a sheet of paper may be placed to have the surface thereof indented or perforated so that writing upon the same cannot be altered after such indentation or perforation. If it is attempted to write upon the check after the 20 same has been operated upon by the device, the ink will run into the broken parts of the paper and all negotiability of a check so operated upon will be destroyed. It is 25 an object of the invention to provide such a device of extremely simple construction and of such size that it can be readily carried on the person, if desired.

It is a further object of the invention to 30 provide such a device in which a plurality of movable serrating devices are employed so that the same can be brought into various degrees of alinement.

These and other objects and advantages 35 of the invention will more fully appear from the following description made in connection with the accompanying drawings in which like reference characters refer to the same parts throughout the different views, 40 and in which—

Figure 1 is a view in side elevation of the device a different position of the same being shown in dotted lines;

Fig. 2 is a plan view illustrating the use 45 of the device;

Fig. 3 is a partial view in side elevation on an enlarged scale; and

Fig. 4 is a view in end elevation as seen 50 from the left of Fig. 1, the same being shown on an enlarged scale and with the perforating rollers pressed together.

Referring to the drawings, the device is seen to comprise a member 1, which, in the embodiment of the invention, illustrated, is 55 formed of a flat piece of thin resilient ma-

terial bent at its middle portion into substantially U-shape with the arms 1^a and 1^b thereof slightly diverging and the ends of the arms slightly inturned toward each other at right angles. Mounted upon each of the 60 arms 1^a and 1^b are U-shaped members 2, the arms of which are of general triangular shape and are formed adjacent their connecting portion with rectangular openings adapted to receive the arms 1^a and 1^b. The 65 bottom or connecting portions of the members 2 thus extend longitudinally of the arms 1^a and 1^b and have their inner surfaces in contact with the outer surfaces of said arms. The inwardly projecting arms 70 of the members 2 are apertured and have journaled therein shafts 3 upon which are rigidly secured within the arms of the members 2, mutilating rollers 4. These rollers are cylindrical in form and have their 75 peripheries stippled, milled or serrated to form mutilating or perforating points. As shown in Fig. 3, in the embodiment of the invention illustrated, the rollers are provided with V-shaped channels arranged at 80 right angles to each other, thereby forming rows of pyramidal projections which are arranged to mesh on the respective rollers to mutilate or perforate the sheet of material placed therebetween.

The use of the device is illustrated in Fig. 2. A check or other sheet of material which is desired to perforate or mutilate is placed between the rollers 4 and the device held in the hand and the rollers moved into 90 contact with the said material. The same can then be drawn through the rollers or the rollers moved along the same, sufficient pressure being placed upon the rollers to 95 suitably operate upon the material. By having the rollers 4 slidable upon the arms 1^a and 1^b, the same can be brought into alinement with each other, as shown in Figs. 1, 2 and 3, or they can be moved more or less out of alinement, thus varying the perforating surfaces which is used. By thus having the rollers relatively movable, any desired width of paper up to the full width of the rollers can be operated upon. The rollers can also be moved to various points 100 along the arms 1^a and 1^b to suit the convenience of different operators. The U-shaped members 2 are frictionally held in any adjusted position on the arms 1^a and 1^b.

From the above description it is seen that 110

applicant has provided an extremely simple form of hand check protector or mutilating instrument. The same comprises few parts and said parts can be easily and 5 cheaply made and yet have great strength and durability.

It will, of course, be understood that various changes may be made in the form, details and proportions of the device without 10 departing from the scope of applicant's invention, which, generally stated, consists in the matter shown and described and set forth in the appended claims.

What is claimed is:

- 15 1. A mutilating instrument comprising a member having slightly diverging arms connected at one of their ends and adapted to move toward and from each other, and a mutilating roller mounted upon each of said 20 arms and disposed between the same with its axis extending longitudinally of said arms, one of said rollers being longitudinally movable with respect to the other.
- 25 2. A mutilating instrument comprising a resilient member bent at its middle portion into substantially U-shape and a mutilating roller movable longitudinally of its axis mounted upon each of said arms, said rollers being located between the arms and having 30 their axes disposed longitudinally of said arms.

3. A hand check protector having in combination a flat resilient bar bent at its middle portion into substantial U-shape with the arms thereof slightly diverging and having their inner ends inturned toward each other, a U-shaped member slidably mounted upon each of said arms with its connecting portion in engagement therewith and its arms directed inwardly thereof, and a serrated roller member journaled in and between the arms of said last mentioned U-shaped member with its axis extending longitudinally of the arms of said first mentioned U-shaped member.

4. A hand check protector having in combination a flat resilient member bent at its middle portion into substantially U-shape with the arms thereof slightly diverging, a U-shaped member mounted upon each of 50 said arms, said last mentioned U-shaped members having apertures in the arms adjacent the connecting portion through which the arms of the first mentioned member pass, said U-shaped members being thus frictionally and slidably mounted upon said arms and a serrating roller journaled in and between the arms of said last mentioned U-shaped members and disposed between the arms of the first mentioned member.

In testimony whereof I affix my signature.
FRANK E. McALLISTER.
